UNITED STATES PATENT OFFICE.

WALTON B. ROBE, OF TOWSON, MARYLAND, ASSIGNOR TO REKEEN TOOL COMPANY, INC., OF BALTIMORE, MARYLAND, A CORPORATION OF MARYLAND.

PROCESS AND APPARATUS FOR RECUTTING OR SHARPENING ALL TOOLS HAVING NUMEROUS FINE CUTTING EDGES.

Application filed August 2, 1927. Serial No. 210,191.

My invention relates to improvements in process and apparatus for recutting or sharpening all tools having numerous fine cutting edges.

5 The object of my invention is to provide a process and apparatus more particularly designed for sharpening files, rasps and dental burrs in which the cutting edges are close together and whereby all of the fine 10 cutting edges are evenly recut or sharpened by the combined action of an acid and an electric current, thus making the tools practically new.

Another object of my invention is to provide 15 a process and apparatus of this character in which any number of tools can be simultaneously recut or sharpened, and in which the acid used in combination with the electric current will last about ten times as 20 long as the acid when used alone without the electric current, and in which every cutting edge is evenly sharpened.

A further object of my invention is to provide 25 a process and apparatus whereby tools of the character heretofore set forth may be more rapidly and cheaply sharpened, and at the same time making the entire tool like new.

In the accompanying drawings:—

30 Figure 1 is a vertical sectional view of a tank or container showing the apparatus by which the process is carried out.

Figure 2 is a top plan view of Figure 1, showing two bars 4 connected by a conductor.

Figure 3 is a perspective view of the tool supporting bar.

Tools of this character, heretofore set forth, have been sharpened by placing them 40 or dipping them in acid, but such a process has been very objectionable in that the acid does not cut evenly, but causes the cutting edges to be rough or leaves a dirty coating on the surface of the tool, thus requiring a 45 separate operation for cleaning the tool. The use of acid alone does not cut uniformly but leaves high sharp points and pits in the cutting edges of the tool, and there has been no way of effectively sharpening this 50 character of tool.

In carrying out my improved process, the apparatus comprises a tank or receptacle 1, made of either glass, wood or other material not effected by the acid, and which as

shown is nearly filled with acid. This acid 55 comprises a mixture of copper sulphate, sulphuric acid, borax and acetic acid. The borax and acetic acid are used as neutralizers to prevent pitting. While I have described copper sulphate it will be understood 60 that silver sulphate or nitrate or any other basic metals in solution can be used.

Arranged in one end of the tank is the electrode 2 to which is connected one terminal 3 of the electric circuit. Arranged in 65 the opposite end of the tank and supported thereby in any desired manner is a metal bar 4 having the other terminal 5 of the electric circuit connected thereto. This bar 5, for the purpose of illustration, is provided 70 with a series of openings 6 in which are arranged the tools 7, which are held therein by set screws 8, by means of which a good electric contact is formed between the bar 4 and the tool. The terminal 3 is the positive terminal, and the terminal 5 is negative. It has been found in actual practice that by passing a current of electricity from the electrode 2 to the tool 7 there is a deposit 75 on the tool and by reversing the current or making the terminal 3 negative and the bar 4 the positive, the metal is taken from the tool and partially deposited on the electrode or carried off by solution, which causes a cutting action or sharpening effect on the 80 fine cutting edges of the tool.

It has, however, been found that the most effective process and apparatus of sharpening tools of this character is to employ an alternating current. When using the alternating current the metal from the electrode 2 is rapidly carried across through the solution and deposited on the tool, then by the alternating current is rapidly removed from the tool and carried back rapidly to the electrode, causing a cutting or sharpening action. It has been found that a low voltage 90 is much more effective than a high voltage current, and will not cause any high points or pits in the cutting edges of the 95 tool but will sharpen the tool and cause it to have the appearance of a new tool. The invention, as heretofore stated, is more especially designed for dental burrs, files, rasps, and any tool having a large number 100 of fine cutting edges arranged so close together that it can not be sharpened in the usual manner of sharpening tools.

It has also been found that a pulsating current is very effective in carrying out my invention.

In Figure 2 I have shown two bars 4 connected by a conductor 9 and it will be understood that any number or form of tool support can be used.

Having thus fully described my invention what I claim is:—

- 10 1. The process of sharpening tools consisting in passing an electric current from an electrode through a solution of copper sulphate, sulphuric acid, borax and acetic acid to the tools.
- 15 2. The process of sharpening tools consisting in passing an alternating electric current from an electrode through a solution of copper sulphate, sulphuric acid, borax and acetic acid to the tools.
- 20 3. The process of sharpening tools consist-

ing in depositing and removing metal from tools by an alternating electric current passing through a solution.

4. The process of sharpening tools consisting in depositing and removing metal from tools by an alternating electric current passing through a solution of copper sulphate.

5. The process of sharpening tools consisting in depositing metal upon a tool by an electric current passing through a solution and removing the metal from the tool by reversing the electric current.

6. The process of sharpening tools consisting in passing an electric current from an electrode through a solution of copper sulphate, borax and acetic acid to the tools.

In testimony whereof, I have signed this specification.

WALTEN B. ROBE.
